[57] **CLAIM**

The ornamental design for housings for electronic circuits, as shown and described.

DESCRIPTION

FIG. 1 is a front, top and right side perspective view of a housing for electronic circuits showing my new design;

FIG. 2 is a top-plan view thereof;

FIG. 3 is a bottom-plan view thereof;

FIG. 4 is a front-elevational view thereof;

FIG. 5 is an inverted rear elevational view thereof; and

FIG. 6 is a left side elevational view thereof, the right side elevational view thereof being a mirror image.
